COMBINED FLOODLIGHT AND EXTENSION ARM

Reynolds B. Winslow, Syracuse, N.Y., assignor to Crouse-Hinds Company, Syracuse, N.Y., a corporation of New York

Filed Feb. 18, 1965, Ser. No. 83,860

Term of patent 14 years

(Cl. D48—23)

FIGURE 1 is a side elevational view of a combined floodlight and extension arm showing my new design, the extension arm being shown broken away to indicate indeterminate length.

FIGURE 2 is a rear elevational view of the combined floodlight and extension arm shown in FIGURE 1, the extension arm being shown fragmentarily therein for convenience of illustration.

FIGURE 3 is a front view of the combined floodlight and extension arm shown in FIGURES 1 and 2.

The dominant features of my design reside in the portions shown in full lines.

I claim:

The ornamental design for a combined floodlight and extension arm, as shown and described.
